NESTABLE MUSIC STAND

Harold H. Wiese, 804 Spaulding, Davenport, Iowa

Filed Jan. 20, 1964, Ser. No. 78,259

Term of patent 14 years

(Cl. D33—10)

FIG. 1 is a side elevation of the nestable music stand as seen from the left front thereof.

FIG. 2 is a perspective of the nestable music stand as seen from the rear.

FIG. 3 is a perspective of the nestable music stand as seen from the front and one side thereof.

FIG. 4 is a perspective of the nestable music stand as seen from the front and other side thereof.

I claim:

The ornamental design for a nestable music stand, substantially as shown.
